UNITED STATES PATENT OFFICE.

JOSEPH H. DOW AND HERBERT H. DOW, BOTH OF CLEVELAND, OHIO; SAID
HERBERT H. DOW ASSIGNOR TO WILLIAM CHISHOLM, OF SAME PLACE.

ROTARY STEAM-ENGINE.

SPECIFICATION forming part of Letters Patent No. 403,335, dated May 14, 1889.

Application filed August 25, 1888. Serial No. 283,751. (No model.)

To all whom it may concern:

Be it known that we, JOSEPH H. Dow and HERBERT H. Dow, of Cleveland, in the county of Cuyahoga and State of Ohio, have invented 5 certain new and useful Improvements in Rotary Steam-Engines; and we do hereby declare the following to be a full, clear, and exact description of the invention, such as will enable others skilled in the art to which it pertains to 10 make and use the same.

Our invention relates to improvements in the rotary engine shown and described in Letters Patent No. 392,545, granted November 6, 1888; and it consists in certain features of 15 construction and in combination of parts hereinafter described, and pointed out in the claims.

In the accompanying drawings, Figure 1 is an elevation in longitudinal section through 20 the center of the engine. Fig. 2 is an end elevation, partly in section, the cylinder-head of the foreground being removed and portions being broken away to show the construction.

A represents the body or shell of the engine, to which are detachably secured heads B, the latter having suitable boxes, in which is journaled the engine-shaft D. The shell A is provided with internal flanges, a, these flanges being "faced off" and screw-threaded 25

30 at the internal periphery to receive disks C, the latter being screw-threaded at C' for engaging the aforesaid flanges. The two flanges and the backs of these disks are separated to form steam-chamber A', the latter connecting 35 with induction-pipes a'. The shell A terminates in a supporting-base, A², to which exhaust-pipe a² is attached, the latter connecting with exhaust-chamber A³. The disks C, on the outer faces thereof, are provided, re-

40 spectively, with series of curved wings or chutes c, each series being arranged in concentric order with the axis of the shaft D. The different wings c of a series are separated the one from the other to form ports c', the latter being preferably arranged in the curved order shown in Fig. 2. (See dotted line x x with center x'.)

45 E are rotating disks or wheels, the same being mounted on and secured to shaft D. These 50 disks have long hubs E', projecting toward

each other and nearly meeting on the shaft, leaving room only for the intermediate disk, d, the latter also being made fast to the shaft. The faces of wheels E are provided with series of curved buckets e, that alternate with 55 wings c, a series of buckets operating between series of wings, and vice versa, the vents e' being laid out on curved lines the reverse of line x x, and these vents e' being less in aggregate area of discharge than the aforesaid 60 ports c', the object being to utilize the reactive force of steam rather than the impact of steam, and by means of the ports and vents being arranged on curved lines, deflecting in opposite directions, as shown, the openings of 65 the different series of buckets and wings can be made to cross each other at substantially equal angles throughout the series and at such angles as will give the greatest effectiveness, such angles at present advised being approximately right angles. This class of 70 engines is intended to run at a very high speed, and to avoid friction the disk C and wings c do not come in contact with the opposing 75 wheels E and buckets e, although the clearance at the ends of the wings and buckets is very small—say a two-hundredth part of an inch, more or less.

Heretofore the great difficulty has been to hold the shaft D endwise. The high speed 80 attained was such that ordinary collars caused too much friction, and were consequently worthless for such purpose.

Our improved mechanism is as follows: The aforesaid disk d overlaps in radial direction 85 the inner periphery of the disks C. The latter are screw-threaded at c² to engage rings or collars G, the latter being screw-threaded externally. These rings are provided with lock-nuts g. The rings are adjusted toward 90 or from disk d to leave suitable and equal passage ways or ports, i and i', for the passage of steam from chamber A' to chamber K, from which latter the steam passes between the disks C and opposing wheels E via ports 95 c and vents e' to the exhaust-chamber. Rings G having been adjusted and secured by the respective lock-nuts, so long as there is no disturbing cause spaces i and i' will remain equal and an equal volume of steam will issue 100

to the two sides of the engine; but suppose from any cause the shaft were moved toward, for instance, what is the right-hand side, as shown in Fig. 1, such a movement would partially close the passage-way or port i , and would consequently shut off a portion of the steam to the right-hand side of the engine, and would at the same time further separate disk C and wheel E at this side of the engine.

10 The reduction of steam-volume and the widening of steam-space between the disk and wheel would tend to diminish the endwise pressure on the shaft, while on the other side of the engine the reverse would take place—that is to say, steam-space i' would enlarge, thereby giving greater volume of steam on this the left-hand side of the engine, and the disk and wheel on the left-hand side of the engine would approach each other, thereby decreasing the steam-space between the two, and consequently giving greater steam-pressure to act in the opposite direction endwise of the shaft, all of which would tend to return the shaft to its central or normal position lengthwise of the engine. The apparatus whereby a steam-balance is thus had is very sensitive, by reason of which the buckets may run in close proximity to their seats without absolute contact, thus avoiding all friction except at the journal-bearings of the engine-shaft. In place of a single disk, d , rigidly secured to the shaft, two such disks might be employed, and these might be adjusted lengthwise of the shaft instead of the adjusting-rings G; also, the curved lines on which the vents and ports are laid out need not necessarily be on true circles.

What we claim is—

1. In a rotary steam-engine, the combination, with stationary disks with steam-chamber located between the disks and opposing rotating wheels located outside the disks, the wheels being mounted on the engine-shaft, substantially as indicated, of an engine-shaft, and a disk mounted on the engine-shaft between the line of the stationary disks, said rotating disk extending into and dividing the eduction of the said steam-chamber, substantially as set forth.
2. In a rotary engine, the combination of shaft carrying with it two wheels and a disk between them, these wheels being opposed in-

wardly by stationary disks, the central or revolving disks being opposed on opposite sides by rings connected with the stationary disks, leaving annular spaces between the central disk and rings that act as steam-ports, substantially as set forth.

3. The combination, with a rotary engine of the variety indicated, having stationary disks and movable disk, the latter being mounted on the engine-shaft and extending into the steam-space between the stationary disks, of rings mounted on such stationary disks and adjustable toward and from the rotating disk, substantially as set forth.

4. The combination, with stationary disks and intervening rotating disk, the latter being mounted on the engine-shaft, substantially as indicated, of screw-threaded rings engaging the stationary disks, such rings being adjustable toward and from the rotating disk, and lock-nuts mounted on the respective rings, substantially as set forth.

5. In a rotary engine, the combination of stationary disks and rotating wheels, the former bearing wings separated so as to form intervening ports and the latter bearing buckets separated so as to form intervening vents, the system of ports and vents being arranged in curved lines deflecting in opposite directions, the aggregate area of the vents being less than the aggregate area of the ports, substantially as set forth.

6. In a rotary engine, the combination, with stationary disks provided with a curved series of ports, and revolving wheels provided with a curved series of vents, the latter being arranged in curved lines deflecting in opposite directions to those of the ports, said revolving wheels being provided with inwardly-projecting limbs, of a revolving disk located on the shaft between the adjacent ends of said limbs and extending into and dividing the steam-outlet of the steam-chamber, substantially as set forth.

In testimony whereof we sign this specification, in the presence of two witnesses, this 15th day of May, 1888.

JOSEPH H. DOW.
